(57) **CLAIM**

The ornamental design for a rubber glove with sponge covering, as shown and described.

DESCRIPTION

FIG. 1 is a perspective view of a rubber glove in a first embodiment with a sponge covering, showing our new design;

FIG. 2 is a back plan view of FIG. 1;

FIG. 3 is a right elevational view of FIG. 1;

FIG. 4 is a left elevational view of FIG. 1;

FIG. 5 is a top plan view of FIG. 1;

FIG. 6 is a bottom plan view of FIG. 1;

FIG. 7 is a perspective view of a rubber glove in a second embodiment with removable sponge, showing our new design

FIG. 8 is a perspective view of the removable sponge of FIG. 7;

FIG. 9 is a back plan view of FIG. 8;

FIG. 10 is a right elevational view of FIG. 8;

FIG. 11 is a left elevational view of FIG. 8;

FIG. 12 is a top plan view of FIG. 8;

FIG. 13 is a bottom plan view of FIG. 8; and,

FIG. 14 is a right-side perspective view of FIG. 8.

The broken lines in FIGS. 1-14 are included for the purpose of illustrating portions of rubber glove with sponge covering that forms no part of the claimed design.
